Primary Examiner — Cynthia R Underwood(74) *Attorney, Agent, or Firm* — MacCord Mason PLLC(57) **CLAIM**

The ornamental design for a reusable flexible sandwich holder, as shown and described.

DESCRIPTION

FIG. 1 is a perspective view of a reusable flexible sandwich holder showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an alternate side perspective view thereof, showing the reusable flexible sandwich holder in use.

The broken lines shown in the drawings depict environment and portions of the reusable flexible sandwich holder that form no part of the claimed design.

1 Claim, 4 Drawing Sheets(56)
